(57) **CLAIM**

I claim the ornamental design for a vehicle door handle, as shown and described.

DESCRIPTION

Door handle designed for use on motor vehicles. FIG. 1 is a front elevational view of a vehicle door handle showing my new design, the undisclosed rear is not part of the claimed design;

FIG. 2 is a right perspective view thereof; and,

FIG. 3 is a left perspective view thereof.

1 Claim, 2 Drawing Sheets
